UNITED STATES PATENT OFFICE.

FRANK W. HENRIKSON, OF MULBERRY, KANSAS.

LINK COUPLER.

Application filed September 13, 1921. Serial No. 500,337.

To all whom it may concern:

Be it known that I, FRANK W. HENRIKSON, a citizen of the United States, residing at Mulberry, in the county of Crawford, 5 State of Kansas, have invented certain new and useful Improvements in Link Couplers, of which the following is a description, reference being had to the accompanying drawing, and to the figures of reference marked 10 thereon.

This invention relates to link couplers and more particularly to an improved type of link coupler connected to a dinkey or other motor engine and adapted to be coupled to the usual hook on a mine car.

At the present time, dinkeys are coupled to mine cars by three chain links. One of the links of the chain is coupled to the clevis of the dinkey drawbar by the usual coupling 20 pin, while the other link of the chain is passed over the stationary hook on the mine car. When the dinkey is to be uncoupled from a mine car, the operator on the dinkey pulls the pin which couples the link of the 25 chain with the drawbar on the dinkey, which leaves the chain attached to the hook on the car. It is desirable to uncouple the link from the hook, leaving the link attached to the dinkey and not to the mine car, but this 30 is not practical because there is no operative on the mine car to do this uncoupling. The operative is on the dinkey and he cannot uncouple the links from the hook on the car. When the operator on the dinkey releases the 35 pin to uncouple the links from the drawbar, the links remain with the car so that the next time a coupling is necessary, the operative on the dinkey has to supply a new chain which he couples by means of the coupling 40 pin to the drawbar of the dinkey and this link is then hooked over the hook of the mine car to complete the coupling.

The present invention permits the dinkey to be coupled and uncoupled from the mine 45 car by an improved link in which the operative on the dinkey can uncouple the link from the stationary hook on the car, thus leaving the link attached to the drawbar on the dinkey so that it can be used again when 50 another car is to be coupled.

Another object of this invention resides in providing such a construction in which the link can be coupled and uncoupled by an operative located at any convenient place on 55 the dinkey.

Yet another object of this invention re-

sides in providing a coupling link and operating mechanism therefor which permits the uncoupling to take place automatically on the creation of a slack between the dinkey 60 and mine car.

Another feature of this invention resides in providing a flexible link made collapsible in order to prevent the link from being damaged when the dinkey and mine car come 65 together.

A further object of the invention is to provide such a collapsible link which can fold upwardly only, so that the link will always be rigid when lowered in order to permit 70 it to pass over the stationary hook on the mine car.

Still another feature of the invention resides in providing means to maintain the link proper in a normally downwardly inclined position so as to permit it to more easily withdraw from the hook on the mine car on the creation of a slack.

Still another object resides in providing the link with a collapsible connection with 80 the dinkey drawbar and in providing means for raising and lowering the links, said means being constructed to maintain the connection rigid during the raising and lowering.

These and other objects will be manifest from a perusal of the following specification when taken in connection with the accompanying drawing, in which—

Figure 1 is a side elevation of the improved coupler showing its relation to the dinkey;

Fig. 2 is a plan view thereof slightly enlarged;

Fig. 3 is a sectional view showing the 95 chain control for raising and lowering the link proper;

Fig. 4 is a detail view of the link construction;

Fig. 5 is a section on the line 5—5 of Fig. 100 1, and

Fig. 6 is a section on the line 6—6 of Fig. 1.

Referring now to the drawings in detail, the lower frame 1 of the dinkey is provided 105 with a suitable squared aperture 2 for the reception of the drawbar 3. The drawbar is provided with a draft device comprising a plate 4 suitably bolted as at 5 to the inside of the dinkey frame wall 1, and provided 110 with a central aperture through which freely passes the drawbar 3. On each side of this

aperture, the plate is provided with integral webs 6 which form guides for the drawbar and adjacent these guides the plate is formed with studs 7 providing centering means for coiled springs 8 which are compressed between the plate and a head 9 fixed to the outer end of the drawbar. This head is likewise provided with centering studs 10 for the springs 8. By this construction, the 10 coupling is relieved of all sudden shocks incident to the coupling operation.

The outer end 11 of the drawbar 3 or the drawbar head is apertured as usual to receive the coupling pin 12 which passes 15 through a likewise apertured tongue 13 of the improved link coupling.

This coupling is composed of two end blocks 14 and 15 concatenated by a series of spaced links presently to be described. 20 The inner block 14 is the member which is formed with the tongue 13. The outer end of this block 14 is preferably rounded like a link as at 16 and it is formed with three slots or recesses 17, 18 and 19. The outer 25 slots 17 and 19 receive the rounded ends of the connecting links 20 and 22, while the recess 18 receives the link 21 and also forms a passage for a chain 23. This chain is attached as at 24 to the upper portion of 30 link 21 and passes over the top of the inner rounded end thereof into passage 18 and then beneath a friction roller 23' which is carried by the block 14 and is arranged in this recess 18 to serve as a guide for the 35 chain 23. The drawhead 11 is cut away in the form of an arcuate slot 25 to permit the passage of the chain upwardly through the drawhead, the slot being wide enough to accommodate the relative pivotal movement 40 of the link in a horizontal plane.

In addition to the three links 20, 21 and 22, there are two outside links 26 and 27. The links 20, 21, 22, 26 and 27 are pivoted to the block 14 by the pivotal pin 28 which 45 is provided with cotter pins 29 or other fastening devices as usual.

As shown clearly in Fig. 5, the intermediate link 21 is wider than links 20 and 22, 26 and 27. Links 20, 21 and 22 are provided 50 on their outer ends with a cross bar 30 attached by screws 31 or other suitable means. This bar is located just at the point where the flat portion of the link merges into its rounded end and constitutes a stop 55 which cooperates with lugs 32 formed on the under surfaces of the rounded ends of the intermediate links 33, 34, 35 and 36 to prevent links 33 to 36 dropping below a horizontal plane with reference to the links 20, 60 21, 22, 26 and 27, or to prevent the pivotal connection breaking downwardly. These links 33 to 36 are pivotally joined to links 20, 21, 22, 26 and 27 by means of pivotal pin 37 likewise provided with cotter pins on 65 its extremities for holding the links as-

sembled. The outer rounded ends of links 33 to 36 inclusive, fit into spaced slots formed in the outer block 15 and are joined thereto by the pivotal pin 38. The under surface of the outer rounded portions of links 33 to 36 are provided with lugs 39 which cooperate with abutments or walls 40 in the slots of the block 15 to provide stops to prevent the block 15 swinging or breaking below a horizontal plane relative to links 33 to 36, inclusive. 75

Block 15 is rounded on its extreme end and is provided with the lateral cutouts 41 and 42, each having a face 43 which is not quite vertical and a lower face 44 which is inclined slightly downwardly from a true horizontal plane. 80

The link proper 45 is provided with two hooked or inwardly projecting lugs which pass into lateral bores 46 and 47 in an intermediate portion 48 of the block 15. By means of this construction, the link proper is pivotally attached to the block and is capable of swinging to almost a vertical position as when raised and also to a lowered 90 position in which the link is disposed below the horizontal plane of the chain. This downwardly inclined position of the link 45 permits it to slip out of the stationary hook 46 more readily on the creation of a slack. 95

Referring now to the chain 22 for raising and lowering the link proper 45, it will be seen that the upper end of the chain is provided with a connecting rod 47 formed with an eye 48 attached to an L-shaped arm 49 pivoted to an oscillatable rod 50 journaled on the frame 1 of the dinkey above the rod 47. A coiled spring 51 surrounds rod 50, the same being attached to the frame at one end and the other end 52 to the arm 49. 100

The rod 50 is likewise provided with a connecting link 53 extending upward vertically and is formed with a slot 54 to receive an operating rod 55 running to any convenient point on the dinkey. By means of this construction an operator on the dinkey can pull rod 55 which will oscillate rod 50 and put spring 51 under tension since arm 49 cannot move due to the drawing load between the dinkey and the train of cars. However, as soon as a slack arises, this load is released and arm 49 is raised by the tension of coiled spring 51 whereby to automatically lift chain 23. The chain 23 being connected to link 21, all the links are raised since they cannot break at their junction, due to the locking abutments 30, 32 and 39 and 40. It will be noted in Fig. 1 that the slot 25 is wide enough to permit considerable back and forth play of link 47. This play when cooperating with the pivotal connection of the link 47 to the upper end of the flexible chain, together with the pivotal connection between the link 47 and the arm 49, plus also the pivotal connection of the arm 49 110

115

130

with rod 50, provides a sufficient lost motion in the connection between the chain links and the rod 50, to accommodate the usual draft movement of the drawhead 11 as it compresses the spring 8. It is also manifest that the chain 23 itself possesses a certain amount of inherent play between the links to abet this lost motion connection.

Hence it will be seen that the link 45 is swung upwardly to clear the hook 46. This action is automatic on the creation of a slack.

When uncoupled, the link 45 is carried in raised position and is dropped at the proper time to pass over hook 45 to couple to a mine car.

While the connected links are not permitted to break downwardly because of the locking lugs 30, 32 and 39 and 40, the links are free to collapse upwardly to prevent the destruction of the link in case of collision. It is not intended to restrict the invention herein to the precise form illustrated, and described except in so far as it is limited by the terms of the appended claims.

Having thus described the invention, what I claim as new and desire to secure by Letters Patent, is:—

1. In combination with a draw-bar of a dinkey or the like, a coupling member adapted to detachably couple to the cooperative coupling member of a mine car, a collapsible connection between said draw-bar and said first-mentioned coupling member, said connection being pivotally connected to said draw-bar to swing in a horizontal plane, and means for raising and lowering said first-mentioned coupling member, said collapsible connection and pivotal connection being constructed and arranged to maintain the connection substantially rigid during the raising and lowering movement.

2. In combination with the drawbar of a dinkey or the like, a link coupling adapted to couple to the hook of a mine car, a series of pivotally connected links pivotally connected to said drawbar to swing in a horizontal plane, means to prevent the pivotal connection between said links and between said links and said draw-bar, from breaking downwardly, and means for raising and lowering the first of said series of links whereby said connection between said drawbar and coupling link is maintained rigid during the raising and lowering movement.

3. In combination with the drawbar of a dinkey, a series of links pivoted to said drawbar, a second series of links pivotally

connected to said first mentioned links to break upwardly only, a link coupling pivotally connected to said second series of links to break upwardly only, and means for raising and lowering said first mentioned links to swing said link coupling to raised or lowered position.

4. In combination with the drawbar of a dinkey, a recessed block pivoted thereto to swing in a horizontal plane, a friction roller journaled in said recess, a series of links pivoted to said block for vertical oscillation, a second series of links pivoted to said first mentioned links, a link coupling pivoted to said second named links, the pivotal connections between said links and between said links and link coupling being constructed to prevent downward pivotal movement of said members below the horizontal plane of movement of said recessed block, a chain connected to the upper portion of one of said first named links, said chain passing over said link into the recess of said block and beneath said friction roller, a lever passing downwardly through a recess in said drawbar and connected to said chain, and means for raising and lowering said lever.

5. In combination with the draw bar of a dinkey or the like, a link adapted to couple to the hook of a mine car, a connection between said drawbar and link, and means for automatically raising said link on the creation of a slack.

6. In combination with the frame of a dinkey, a drawbar resiliently connected thereto, a link adapted to couple to the hook of a mine car, a collapsible connection between said drawbar and link, means for automatically raising and lowering said link on the creation of a slack, said means and said connection being arranged to maintain the connection substantially rigid during the raising and lowering of said link.

7. In combination with the drawbar of a dinkey, an outer block, an inner block adapted to be pivotally connected to said draw-bar to swing in a horizontal plane a collapsible linkage connection between said inner and outer blocks constructed and arranged to be maintained substantially rigid on swinging movement, a link coupling pivotally connected to said outer block and adapted to normally lie downwardly inclined to a horizontal plane, and means for operating said linkage connected to raise and lower said link.

In testimony whereof I affix my signature.
FRANK W. HENRIKSON.
